UNITED STATES PATENT OFFICE.

HARVEY J. YAGER, OF SEATTLE, WASHINGTON.

MOVABLE RAIL-CROSSING.

1,266,371.

Specification of Letters Patent. Patented May 14, 1918.

Application filed October 8, 1915. Serial No. 54,840.

To all whom it may concern:

Be it known that I, HARVEY J. YAGER, a citizen of the United States, residing at Seattle, in the county of King and State of Washington, have invented certain new and useful Improvements in Movable Rail-Crossings; and I do hereby declare the following to be a full, clear, and exact description of the invention, such as will enable others skilled in the art to which it appertains to make and use the same.

The invention relates to improvements in railway crossings and other intersecting rails.

15 The object of the present invention is to improve the construction of railway crossings and the like and to provide a simple, practical and comparatively inexpensive device adapted to afford continuous treads and continuous flange receiving grooves at street railway crossings and other points of track intersections of street and other railways whereby the injury incident to the contact of the wheels of the rolling stock with the 20 ends of the rails will be entirely eliminated and the cost of the upkeep of a railroad greatly reduced.

A further object of the invention is to provide rotatable frog members having 30 spaced tread portions and intervening flange receiving grooves and adapted to be turned in clockwise and counter-clockwise direction for arranging the grooves and the tread in alinement with the grooves and treads of the 35 rails of either track to form continuations of the same.

Another object of the invention is to enable the frog members to be rotated so that 40 separate tread surfaces will be presented to the intersecting rails whereby the wear on the frog members will be uniformly distributed over both of the tread surfaces.

The invention also has for its object to provide electrically controlled means for 45 simultaneously rotating the frog members at the four corners of a crossing and for locking the said frog members in either of their positions.

With these and other objects in view the 50 invention consists in the construction and novel combination and arrangement of parts hereinafter fully described, illustrated in

the accompanying drawings and pointed out in the claims hereto appended, it being understood that various changes in the form, 55 proportion and minor details of construction may be resorted to without departing from the spirit or sacrificing any of the advantages of the invention.

In the drawings—

Figure 1 is a plan view of a railway crossing constructed in accordance with this invention,

Fig. 2 is a longitudinal sectional view through one of the corners of the crossing, 65

Fig. 3 is a detail sectional view on the line 3—3 of Fig. 2,

Fig. 4 is an enlarged sectional view taken longitudinally of one pair of the oscillatory arms,

Fig. 5 is a transverse sectional view taken substantially on the line 5—5 of Fig. 4,

Fig. 6 is a similar view taken substantially on the line 6—6 of Fig. 4,

Fig. 7 is a sectional view taken substantially on the line 7—7 of Fig. 4,

Fig. 8 is a reverse plan view of one of the corner bearing plates,

Figs. 9 and 10 are detail views of the gear element of the rotary frog member, 80

Fig. 11 is a detail view of one of the oscillatory arms having the inwardly projecting spur teeth,

Fig. 12 is a detail perspective view of one of the keys for securing the oscillatory arms 85 in the recesses of the vertical pivot or support.

Fig. 13 is a diagrammatical view, illustrating the signal circuits and the controlling means.

Like numerals of reference designate corresponding parts in the several figures of the drawings.

In the accompanying drawings in which is illustrated the preferred embodiment of 95 the invention as applied to a railway crossing 1 designates rails arranged in pairs at right angles to each other and connected at their ends to corner bearing plates 2 each preferably consisting of a casting provided 100 with inner and outer rail attaching means for connecting the said rails 1 with the casting 2 and for also attaching outer rail sections 3 with the said castings or corner bear-

ing plates. The inner attaching means comprises lugs or flanges 4 and 5 arranged in pairs and spaced apart to receive the web 6 of the rails 1 which are sheared off at their 5 ends to form projecting bottom flanges 7 that extend into recesses 8 of the corner bearing plates.

The projecting flanges 4 and 5 which are approximately inverted L-shaped in cross 10 section as clearly illustrated in Fig. 3 of the drawings are riveted or otherwise secured to the webs 6 of the rails 1 against which they are fitted. The outer attaching means for securing the outer rail sections 3 to the corner bearing plates consist of projecting flanges 9 and 10 spaced apart to receive the webs of the rail sections which are sheared off to leave projecting bottom flanges 11 for extending into outer bottom recesses 12 of 15 the bearing plate 2. The flanges 9 and 10 are substantially the same as the flanges 4 and 5 with the exception that the latter are slightly longer than the outer projecting flanges 9 and 10. The corner bearing plates 20 extend over the projecting bottom flanges of the rails 1 and 3 and the said rails are connected at each of the corner bearing plates by a bottom connecting plate 13 to which the bottom flanges of the said rails 25 are riveted or otherwise secured. The projecting flanges of the corner plates are cut away at 14 to afford access to the rivets 15 or other fastening devices and after the parts have been assembled filler blocks 16 30 are secured in the said recesses 14 as clearly illustrated in Fig. 2 of the drawings. Each of the connecting plates 13 is arranged upon a tapered or beveled compression plate 17 interlocked with the corner bearing plate 35 and connecting plate by pins 18 arranged vertically and piercing the projecting bottom flanges of the rails, the connecting plate 13 and fitted in sockets 19 and 20 in the corner bearing plates and the compression plate. 40 The base or compression plates 17 are riveted or otherwise secured to tie bars 21 extending longitudinally of the rails 1 from one point of intersection to the other and fastened at intervals to the bottom flanges 45 of the said rails by rivets 22 or other suitable fastening devices and also secured to the said rails and the connecting plates by the rivets 15. The rivets 23 which pierce the crossed or overlapped ends of the tie 50 plates or bars 21 and the base plates 17 have their heads countersunk in the latter as clearly as shown in Fig. 2 of the drawings. Any other suitable fastening means may of course be employed for securing these parts 55 together. The terminal portions of the tie bars or plates 21 are angularly bent as shown at 24 to conform to the configuration of the beveled edges of the base plate 17 and the construction forms a solid truss like 60 65 structure and rigidly connects the parts to-

gether so that it is unnecessary to place a tie or similar support under the adjacent ends of the rails of the crossing. The corner bearing plate is of irregular rectangular shape and the bottom connecting plate 70 which extends outwardly beyond the side faces of the corner bearing plate is provided in its projecting portions with spike receiving recesses or openings 25 for the reception of suitable fastening means for securing the 75 crossing in position. The crossing is provided at each of the rails with a flange way or groove 26 formed by longitudinally disposed guide plates 27 preferably arranged in pairs and connected by an angularly disposed portion 28 fitted against the adjacent side face of the corner bearing plate. The guide plates which are spaced from the adjacent sides of the rails 1 by filler bars 29 preferably extend to the centers of the rails 80 1 midway between the corner bearing plates 2 as clearly shown in Fig. 1 of the drawings but the guide plates may be of any desired length as will be readily understood and they are secured to the rails 1 by rivets 90 or other suitable fastening devices which pass through the guide plates, the rails, and the filler bars. The filler bars which are preferably made in sections as shown to facilitate casting and assembling the parts are 95 provided in their bottom faces or edges with recesses or grooves 30 to receive the heads of the rivets 15 and 22 which secure the tie bars or plates to the bottom flanges of the rails. Guide plates 31 are also located at 100 the other side faces of each of the corner bearing plates as clearly shown in Fig. 1. These plates 31 have terminal attaching portions and angularly disposed connecting portions, the attaching portions being secured to the adjacent rail. The terminal portions of the plates 31 form outer grooves 105 32 for guiding the flanges of the wheels and the attaching portions of the said plates 31 have the flanges 9 interposed between them 110 and the rails.

Each of the corner bearing plates is provided in its upper face with a cylindrical bearing recess or socket 34 receiving a circular rotary frog member 35 provided with 115 a flange way or groove 36 adapted to be arranged in alignment with the flange ways or grooves of the intersecting rails to form a continuation of the grooves or ways for safely guiding the flanges of a wheel at the 120 crossing. The rotary frog member is provided at opposite sides of the groove 36 with tread faces 37 which are arranged in the same horizontal plane as the tread faces of the heads of the rails and fixed tread 125 plates 38 are suitably secured to the corner bearing plates and are located between the sheared portions of the rails and the rotary frog member as clearly shown in Fig. 2 of the drawings. By this construction a con- 130

tinuous tread surface and a continuous flange way or groove is provided at each intersection of the rails so that all hammering of the wheels of a car or the like at intersecting rails is entirely eliminated.

By this construction all jar, vibration and pounding of the rails at a crossing or other intersection is prevented and injury to the rails and the rolling stock from such pounding is eliminated and the cost of the upkeep of a railroad greatly reduced. Each of the 10 rotary frog members is provided with a centrally arranged depending stem 39 extending through a central vertical opening 40 of 15 the corner bearing plate and piercing the base plate 17, the connecting plate and the overlapped terminals of the tie plates or bars. The stem is provided at its lower end with a threaded portion 41 to receive a nut 20 42 and it has a squared portion 43 on which is mounted a gear element 44. The gear element which has a rectangular opening 45 to receive the squared portion 43 of the stem is secured to the latter by a cotter pin 46 and 25 it has an arcuate edge provided with spur teeth 47.

The gear elements 44 of the rotary frogs are actuated by oscillatory arms or bars 48 and 49 disposed diagonally with relation to 30 the crossing and provided at their outer ends with gear elements 50 and 51. The gear elements 50 and 51 are substantially in the form of racks, the teeth of the gear element 50 of the oscillatory bars or arms 48 35 extending outwardly from enlarged terminal portions of the said arms or bars. The other set of arms 49 are provided intermediate of their ends with deflecting bends 52 which arrange the body portions of the said 40 arms 49 below the plane of the other arms 48 and enable the said arms or bars 49 to extend beneath the stem upon which the co-acting gearing elements are mounted. The arms or bars are provided at their outer ends 45 beyond the stems with vertically disposed flanges 53 having inwardly projecting spur teeth constituting the gear elements 51. The gear elements of the stems contiguous to the gear elements 51 are arranged reversely of 50 the gear elements of the other stems in order to mesh with the inwardly projecting teeth of the gear elements 51 of the arms or bars 49. This arrangement effects a rotary movement of some of the frog members 55 clockwise and other of the frog members counter-clockwise when the arms of bars 48 and 49 are oscillated in the same direction and a different tread surface is presented to each of the tracks 60 of the inner section so that neither one of the said surfaces of the rotary frog member is subjected to all of the wear incident to the travel over the crossing. The water collecting in the bearing sockets or 65 recesses 34 is drained from the same by sub-

stantially annular grooves 54 located beyond the bearing faces of the said sockets and communicating with a passage 55 having a tapered or flaring outlet and communicating with openings (not shown) in the connecting plate and the base plate to permit the escape of the water draining from the bearing socket or recess. By this arrangement of the grooves the bearing surfaces of the sockets or recesses 34 are not materially reduced and a maximum bearing surface is afforded.

The inner ends 56 of the oscillatory arms or bars 48 and 49 are arranged in horizontal recesses 57 of an enlarged top supporting portion 58 of a vertical rotary support or pivot 59 having upper and lower journals or pivot portions 60 and 61 and set in a bearing 62 of a bottom bearing plate 63. The recesses 57 are tapered at their inner ends 65 and the ends 56 of the oscillatory arms or bars 48 and 49 are correspondingly shaped. The side walls of the recesses 57 are extended above the upper faces of the arms or bars 48 and 49 and are provided with undercut or dove-tail grooves 64 which receive tapered laterally beveled keys 65 which are secured in interlocked relation with the rotary support or pivot 59 by bolts 66 piercing the keys the arms or bars 48 and 49 and 95 the enlarged upper portion 58 of the rotary pivot or support.

The heads of the bolts 66 are preferably provided with projecting lugs 67 engaging corresponding notches 68 in the keys for 100 locking the bolts against rotary movement. It is preferable to provide bolts of this type throughout the various portions of the construction but any form of bolt may be of course used.

The base plate or bottom bearing plate 63 is mounted upon horizontal beams 69 provided at their end portions with upwardly extending arms 70 arranged vertically and provided with outwardly extending attaching terminals 71. The outwardly extending terminals 71 are secured by suitable fastening devices to the lower faces of inwardly projecting supporting portions 72 of the contiguous connecting plate. The upper 115 journal or pivot portion 60 is mounted in an opening 73 of an upper bearing plate 74 and is reduced to form a shoulder 75 which spaces the upper bearing plate from the upper faces of the keys 65 which retain the 120 oscillatory arms or bars in the recesses of the pivot or rotary support 59. The upper bearing plate is bolted or otherwise secured to open approximately rectangular supports 76, each preferably consisting of a single piece 125 of metal bent to form spaced sides and a connecting top portion, the lower terminals 77 of the sides being bolted or otherwise secured to the bottom bearing plate 63. These open supports 76 arch the oscillatory bars or 130

21

arms 49 and permit the necessary movement of the latter. The oscillatory arms or bars are supported at their outer portions by transversely disposed plates 78 slidably receiving the said arms or bars 48 and secured to the upwardly extending portions 70 of the frame bars or members 69 and provided with opposite shoulders 79 which limit the oscillatory movement of the arms or bars.

10 One of the oscillatory arms or bars 48 is provided with a thickened portion 80 having recesses 81 in its lower face and oppositely beveled at 82 at opposite sides of the recesses to present inclined faces to a pair of spring actuated latch bolts 83 adapted to lock the oscillatory bars or arms in each of their positions. The recesses 81 are located at opposite sides of the thickened portion 80 of the arm or bar 48 and the vertically movable spring actuated bolts are arranged to engage the recesses 81 when the said arm or bar is at the limit of its oscillatory movement. The vertically movable latch bolts are guided in vertically alined openings 84 and 85 in an approximately inverted U-shaped support 86 and a horizontal bar 87 having its terminals 88 bent downwardly and secured to the inner faces of the sides of the U-shaped support 86. The lower terminals 89 of the sides of the inverted U-shaped supports are bolted or otherwise secured to the upper face of a transverse supporting plate 90 upon which are mounted vertically disposed electromagnets 91 adapted when energized to attract armature heads 92 carried by the lower ends of the latch bolts and located beneath the transverse bar 87 as clearly illustrated in Fig. 6 of the drawings. The latch bolts are actuated in 40 their upward movement by coiled springs 93 interposed between the plate 87 and pins or keys 94 secured against movement on the latch bolts by passing through the bolt or other suitable means, but any other desired 45 form of stop may be employed for engaging the upper ends of the coiled actuating springs. The upper engaging ends of the latch bolts are provided at their inner sides with beveled faces 95 to enable them to be 50 readily depressed by the oscillatory arm or bar and they also have beveled faces 96 at their outer sides to enable them to engage or project slightly into the recesses 81 of the oscillatory arm or bar before the latter has 55 reached the limit of its movement and the latches will positively engage the said arm or bar and effectively prevent the same from accidentally being thrown backwardly through contact with the shoulders 79 of 60 the guide plates 78. This insures the locking of the oscillatory arms in proper position at the end of each movement. The electro-magnets 91 which are bolted to the horizontal plate 90 are insulated therefrom by 65 pieces 97 of wood or other suitable material

and they are provided with field pole plates 98 to intensify the action of the electro-magnets.

The oscillatory arms or bars are actuated by stationary electro-magnets 99 arranged in pairs and coacting with movable electro-magnets 100 connected with and carried by the oscillatory arms or bars 48. The stationary electro-magnets which are arranged at a slight angle are provided with arcuate field pole plates 101 having lower integral attaching portions 102 bolted or otherwise secured to transverse plates 103 and insulated therefrom by pieces 104 of wood or other suitable material. The electro-magnets 99 are also connected and braced at the back by plates 105 having angularly disposed end portions and an integral central connecting portion as clearly illustrated in Fig. 1 of the drawings. The movable electro-magnets are provided with field pole plates 106 having upper horizontally disposed attaching portions 107 bolted or otherwise secured to the lower faces of the oscillatory arms or bars 48 and insulated therefrom by pieces 108 of wood or other suitable material and also from the fastening means for securing the parts to the oscillatory bar or member. The field pole plate 106 of the movable magnet is arcuate and its arc co-operates with the arc of the field pole plate of the stationary magnets so that in the oscillatory movement of the arms or bars the field pole plate 106 of the armature movable magnet moves toward and from the field pole plates of the stationary electro-magnets which have double windings and which are wound to a north pole and a south pole so that in the operation of the crossing the field pole plate of the armature magnets 105 will be repulsed by the field pole plate of one of each pair of stationary electro-magnets and attracted by the field pole plate of the other electro-magnet.

Mounted upon the inverted U-shaped support 86 are contacts 109 and 110 consisting of plates arranged in pairs and mounted in insulators 111. The insulators 111 are secured in suitable supports or brackets 112 of approximately Y-shape composed of spaced sides and a connecting portion from which depends a centrally arranged stem. The stem pierces the top of the support 86 and is threaded for the reception of a nut as clearly shown in Fig. 6 of the drawings. The contact plates or pieces 109 and 110 which are designed to be connected with signal light wires are arranged in pairs at opposite sides of the support and the contact plates 110 which are of greater length than the contact plates 109 are resilient and are adapted to be sprung into engagement and electrically contact with the plate 109 whereby one of the signal light circuits will be closed when the oscillatory bars or arms are in each position.

The thickened portion 80 of the oscillatory arm or bar 48 carries an actuating or circuit closing piece 113 constructed of non-conducting material and secured to the said 5 thickened portion 80 by a screw 114 or other suitable fastening device.

The contact actuating piece or member 113 is approximately U-shaped and it has depending sides located at the side edges of 10 the thickened portion of the oscillatory bar or member 48 and the said sides are adapted to flex the contact 110 and force the same into engagement with the contacts 109. When the oscillatory arms or bars are moved 15 in one direction by the energizing of the stationary electro-magnets and the movable electro-magnets the latch bolts are withdrawn by the energizing of the latch operating magnets 91 and as soon as the latter are 20 deenergized by the cutting off of the current the spring operates to force the latch bars upwardly into their engaging position.

The stationary magnets 99 are each provided with windings *a* and *b* and which 25 windings extend in opposite directions so that the north and south poles thereof can be reversed by sending the electrical current first through one winding and then through the other. The movable magnets 100 are 30 each provided with a single winding *c* having their south poles disposed adjacent the stationary magnets 99. A double knife switch 114 is pivotally mounted on a suitable switch board (not shown) and has disposed adjacent thereto contacts 115, 116, 117, 118, 119, 35 120, 121, and 122. Feed conductors 123 and 124 are connected to the contacts 115 and 122 respectively. A conductor 125 is connected to the feed conductor 123 and to the contact 119, and a conductor 126 is connected 40 to the contact 118. Switches 127 and 128 are located adjacent the switch 114 and the switch 127 is adapted to bridge contacts 129 and 130, while the switch 128 is adapted to 45 bridge contacts 131 and 132. A conductor 133 connects the contacts 116 and 129, while a conductor 134 connects the contacts 117 and 130. A conductor 135 connects the contacts 120 and 131, while the conductor 136 50 connects the contacts 121 and 132. When the switch 114 is in engagement with the contacts 116, 115, 117 and 118, electrical current passes to the switch 127 which is of a double knife type, and a conductor 137 is 55 connected to one blade thereof and to one of the magnets 91 which has a conductor 138 connected thereto. The conductor 138 is in turn connected to one end of the winding *a* of one of the magnets 99, causing the current 60 to travel therethrough in the direction indicated by the arrows on the winding *a* to establish a north pole at the end of the magnet which is adjacent the magnets 100, and the south pole at its opposite end. A conductor 65 139 is connected to the other end of the wind-

ing *a* and to one end of the winding *b* of the other magnet 99 of said pair which causes the current to travel therethrough in a reverse direction from that of the first mentioned magnet 99 so as to establish a south 70 pole adjacent the magnet 100 and a north pole at its opposite end.

A conductor 140 is connected to the other end of the winding *b* of the second mentioned magnet 99 of said pair and is connected to one of the magnets 100 which is arranged adjacent said pair of magnets 99, and the electrical current passes through said magnet 100 in the direction indicated by the arrows, so as to establish a south pole 80 adjacent said pair of magnets 99, whereby the magnet 100 will be attracted toward the first named magnet 99 of said pair and repelled by the other magnet 99. A conductor 141 is connected to the magnet 100 and to 85 the other magnet 100 and the electrical current passes therethrough in the direction indicated by the arrow, so as to establish a south pole adjacent the other pair of magnets 99 and a north pole at its opposite end. 90 A conductor 142 is connected to the second named magnet 100 and to one end of the winding *b* of one of the magnets 99 of the second named pair, so as to cause the electrical current to travel therethrough in the 95 direction indicated by the arrows on said winding, thereby establishing a south pole adjacent the second mentioned magnet 100. The last named winding *b* is connected to the winding *a* of the other magnet 99 of 100 said second pair by a conductor 143, so as to cause the electrical current to pass therethrough as indicated by the arrows on said winding *a* thereby establishing a north pole adjacent the second named magnet 100, 105 whereby said magnet 100 will be attracted by the second named magnet 99 and repelled by the first named magnet 99 of said second pair of magnets 99 and which cooperates with the first named pair of magnets 99 110 and magnet 100 in rotating the frogs 35 in one direction. A conductor 144 is connected to the other end of the winding *a* of the second mentioned magnet 99 of the second pair, and is connected to the other blade 115 of the switch 127, whereby a complete circuit is made to all of the magnets for operating the frogs in one direction. A conductor 145 is connected to the switch 128 and to the other magnet 91 which has a conductor 120 146 connected thereto and to the winding *b* of the first mentioned magnet 99 of the first mentioned pair, so as to cause the electrical current to pass through said magnet in the direction indicated by the arrows on said 125 winding *b*, to establish a south pole adjacent the first named magnet 100 and a north pole at its opposite end. The last named winding *b* is connected to the winding *a* of the second mentioned magnet 99 of the first 130

named pair by a conductor 147 which causes a north pole at the end of said magnet which is adjacent the first named magnet 100 and a south pole at its opposite end. A conductor 148 is connected to the winding *a* of the second named magnet 99 of the first named pair and to the conductor 140 so that the electrical current may pass through the first named magnet 100, whereby the same will 5 be repelled by the first named magnet 99 and attracted by the other magnet 99 of the first mentioned pair. A conductor 149 is connected to the conductor 142 and to the winding *a* of the first named magnet 99 of 10 the second mentioned pair, so as to establish a north pole at the end thereof which is adjacent the second named magnet 100. A conductor 150 is connected to the other end of the winding *a* of the first named magnet 99 of 15 the second mentioned pair and is connected to the winding *b* of the other magnet 99 of said second named pair, so as to establish a south pole at the end thereof, which is adjacent the second mentioned magnet 100, whereby the frogs will be moved in 20 an opposite direction from that heretofore described. A conductor 151 is connected to the winding *b* of the second named magnet 99 of the second named pair and to the 25 switch 128 whereby the electrical circuit is completed to the magnets in a reverse direction from the heretofore described, the circuit being completed in the direction just described by moving the switch 144 in engagement with the contacts 119, 120, 121 and 122. A pair of electric lights 152 and 30 153 are located alongside one of the tracks in advance of the crossing and the light 152 is preferably red, while the light 153 is 35 white. A second pair of red and white electric lights 154 and 155 are located on the same track but on the other side of the crossing. A third pair of red and white electric lights 156 and 157 are located on the other 40 track in advance of the crossing and a fourth pair of red and white electric lights 158 and 159 are located on the second named track at a point on the opposite side of the crossing from the lights 156 and 157. A conductor 160 is connected to the conductor 133 45 and to one of the contacts 110. A conductor 161 is connected to the contact 109 which is associated with the said contact 110 and is in turn connected to the electric light 158. A conductor 162 is connected to the electric 50 light 158 and to the electric light 156. A conductor 163 is connected to the electric light 156 and to the electric light 155. A conductor 164 is connected to the electric 55 light 155 and to the electric light 153. A conductor 165 is connected to the electric light 153 and to the conductor 134 which completes an electric circuit when the switch 60 114 is in engagement with the contacts 116 and 117 illuminating the white lights on the 65

first named track and the red lights upon the second named track. When the switch 114 is in the position just described, the frogs are so positioned that the grooves thereof align with the grooves of the first named track. A conductor 166 is connected to the conductor 135 and to the other contact 110. A conductor 167 is connected to the contact 109 which is associated with the second mentioned contact 110 and is connected to the 70 electric light 159. A conductor 168 is connected to the electric light 159 and to the electric light 157. A conductor 169 is connected to the electric light 157 and to the electric light 154. A conductor 170 is connected to the electric light 154 and to the electric light 172. A conductor 171 is connected to the electric light 152 and to the conductor 136 whereby upon moving the switch to engage the contacts 119, 120, 121, 80 122, to move the frogs so that the grooves thereof align with the second named track, the red lights upon the first named track will be illuminated while the white lights upon the second named track will be 85 illuminated, thus indicating to the car on the second named track that the frogs are in a proper position to be crossed and displaying a danger sign to the car approaching upon the first named track. 90

What is claimed is:—

1. A device of the class described including a bearing plate provided with projecting lugs or flanges arranged in pairs, rails having their webs arranged between the 100 members of the pairs of lugs or flanges, said rails being secured to the bearing plate, a connecting plate arranged beneath the bearing plate and secured to the same and the rails and a rotary frog member mounted on 105 the bearing plate and adapted to co-operate with the rails to form a continuous tread and groove or flange way.

2. A device of the class described including bearing plates designed to be located at the four corners of a railroad crossing, intersecting rails connecting the bearing plates, connecting plates located beneath the bearing plates and secured to the same and the rails and longitudinal tie plates or bars 110 115 extending beneath the rails and having overlapped terminal portions secured together and to the rails and rotary frog members mounted on the bearing plates and co-operating with the rails.

3. A device of the class described including bearing plates designed to be located at the four corners of a railroad crossing, rails connecting the bearing plates, beveled base plates supporting the bearing plates, longitudinal tie bars or plates extending along the rails and secured to the bottom flanges of the same and having overlapped terminal portions connected with the bearing plates and the base plates, and rotary frog 125 130

members mounted on the bearing plates and coacting with the rails.

4. A device of the class described including bearing plates designed to be located at the corners of a railroad crossing, rails connecting the plates, base plates located beneath the bearing plates, longitudinal tie plates or bars located beneath the rails and having overlapped terminal portions secured to the base plates and connecting plates interposed between the bearing plates and the base plates, and frog members mounted for rotary movement on the bearing plates and coacting with the rails.

15 5. A device of the class described including bearing plates designed to be located at the corners of a railroad crossing and provided with recesses, rails connecting the bearing plates and having projecting bottom flanges extending into the said recesses, base plates arranged beneath the bearing plates, connecting plates interposed between the base plates and the bearing plates, fastening devices interlocking the said plates and rotary frog members mounted on the bearing plates.

6. A device of the class described including a bearing plate, intersecting rails connected with the bearing plate, guide plates spaced from the rails at the treads thereof to form guide ways or grooves for the flanges of car wheels, filler bars interposed between the guide plates and the rails, and a rotary frog member mounted on the bearing plate and provided with a groove and a tread surface to coöperate with the intersecting rails.

7. A device of the class described including a bearing plate, intersecting rails secured to the bearing plate, outer rail sections also secured to the bearing plate and arranged in alinement with the intersecting rails, relatively long guide plates arranged at the sides of the intersecting rails and spaced from the treads thereof to form flange ways or grooves, said guide plates being provided with an angularly disposed integral connecting portion secured to the bearing plate, short plates having angularly disposed portions arranged at opposite sides of the rail sections and connecting the same with each other and with the intersecting rails and forming flange ways or grooves, filler bars or pieces interposed between the plates and the rails and a rotary frog member mounted on the bearing plate and having a groove and provided with tread surfaces to coact with the said rails and rail sections.

60 8. A device of the class described including rotary frog members designed to be arranged at the corners of a railroad crossing to form continuations of the rails, gear elements connected with the rails and oscillatory means having gear elements provided

with inwardly and outwardly projecting teeth meshing with the gear elements of the frog members and adapted to rotate two of the said frog members clockwise and the other two counter-clockwise.

9. A device of the class described including rotary frog members designed to be mounted at the corners of a railroad crossing, a central pivot, diagonally arranged arms extending from the pivot and carried by the latter, means for operatively connecting the arms with the frog members, and means for oscillating the arms to reversely rotate the said frog members.

10. A device of the class described including frog members mounted for rotary movement at the corners of a railroad crossing, a central pivot or support provided with recesses, arms fitted in the recesses and extending therefrom to the corners of the crossing, plates or keys securing the arms in the said recesses, means for operatively connecting the arms with the frog members and means for oscillating the said arms.

11. A device of the class described including rotary frog members designed to be arranged at the corners of a railroad crossing, a pivot or support provided with recesses and having dove tail grooves in the walls thereof, arms fitted in the said recesses, keys or plates slidably interlocked with the dove tail grooves, and securing the arms in the said recesses, means for operatively connecting the arms with the frog members and means for oscillating the arms.

12. A device of the class described including rotary frog members designed to be arranged at the corners of a railroad crossing, a vertical pivot, oscillatory arms carried by the pivot and operatively connected with the frog members for rotating the same, upper and lower bearing plates receiving the said pivot and open supports secured to the upper bearing plate and receiving two of the said arms.

13. A device of the class described including rotary frog members designed to be mounted at the corners of the railroad crossing, diagonally arranged supporting bars or beams having upwardly extending portions, a lower bearing plate mounted on the said supporting bars or beams and having a bearing, a vertical pivot mounted in the said bearing, arms extending from the pivot and operatively connected with the rotary frog members and plates connecting the upwardly extending portions of the said bars or beams and provided with spaced shoulders arranged to limit the oscillatory movement of the said arms.

14. A device of the class described including a frog member mounted for rotary movement, an oscillatory arm operatively connected with the frog member, electro-magnets mounted in a relatively fixed posi-

tion, an armature electro-magnet carried by the oscillatory arm and means for sending current through the said magnets to cause one of the relatively fixed electro-magnets to repulse and the other to attract the armature magnet.

15. A device of the class described including a frog member mounted for rotary movement, an oscillatory arm operatively connected with the frog member, electro-magnets mounted in a relatively fixed position, an armature electro-magnet carried by the oscillatory arm and means for sending current through the said magnets to cause 10 one of the relatively fixed electro-magnets to repulse and the other to attract the armature magnet, said electro-magnets and movable magnets having arcuate field pole plates arranged in concentric arcs to cause the field 15 pole plates to approach and recede in the oscillatory movement of the arm.

16. A device of the class described including a rotary frog member, an oscillatory arm operatively connected with the frog member, relatively fixed electro-magnets having arcuate field pole plates, an armature electro-magnet carried by the oscillatory arm and provided with an arcuate field pole plate, said magnets having double windings 25 to enable currents to be passed through them in opposite directions, and the relatively fixed electro-magnets being arranged to attract and repulse the armature magnet simultaneously to actuate the oscillatory arm.

30 17. A device of the class described including a rotary frog member, an oscillatory arm operatively connected with the frog member, and relatively fixed and movable electro-magnets having field pole plates provided with attaching portions arranged at 35 an angle and enabling the magnets to be secured to a support and to the oscillatory arm, said magnets being adapted to actuate the arm.

40 18. A device of the class described including an oscillatory arm, a rotary frog member operatively connected with and actuated by the arm, latch members for locking the oscillatory arm in each of its positions, and 45 electro-magnets arranged to withdraw the latch members from their engaging position.

19. A device of the class described including a rotary frog member, an oscillatory arm operatively connected with the frog member, means for actuating the arm to rotate the frog member, and electrically controlled means for locking the oscillatory member in either position.

20. A device of the class described including a rotary frog member, an oscillatory arm operatively connected with the frog

member, spaced spring actuated latch bolts arranged to lock the arm against movement, and electro-magnets adapted to be energized to withdraw the latch bolts from engagement with the oscillatory arm.

21. A device of the class described including a rotary frog member, an oscillatory arm operatively connected with the frog member and provided with spaced recesses 70 and beveled at the outer sides thereof, spring actuated bolts arranged to engage the recesses to lock the oscillatory arm, said bolts having armature heads and electro-magnets arranged to attract the armature heads for 75 withdrawing the bolts from engagement with the oscillatory arm.

22. A device of the class described including an oscillatory arm, a rotary frog member operatively connected with the arm, said 80 arm being provided with spaced recesses, spring actuated latch bolts having beveled faces arranged to be engaged by the oscillatory arm and beveled in the opposite direction to enable them to engage the recesses 85 prior to the limit of the movement of the oscillatory arm, and electrically controlled means for withdrawing the latches from engagement with the oscillatory arm.

23. A device of the class described including rotary frog members designed to be mounted at the corners of a railroad crossing, pivotally mounted oscillatory arms connected with the frog members, relatively fixed electro-magnets arranged in pairs, 95 armature magnets mounted on the said arm and arranged to be attracted and repulsed by the relatively fixed magnets, spring actuated latch bolts arranged to lock the arms at the limit of their movement in each direction, and electromagnets arranged to withdraw the latch bolts from engagement with the oscillatory arms.

24. A device of the class described including an oscillatory arm, a frog member operatively connected with the arm, an approximately inverted U-shaped support having a horizontal top portion, a plate connecting the sides of the support below the top portion thereof, a horizontal base plate, 100 spring actuated bolts mounted in the top of the support and the first mentioned plate and adapted to engage the oscillatory arm, and an electro-magnet mounted on the base plate and arranged to withdraw the latch 110 bolt from engagement with the said arm.

In testimony whereof I affix my signature in presence of two witnesses.

HARVEY J. YAGER.
